ILLINOIS.

Letters Patent No. 65,875, dated June 18, 1867.

IMPROVEMENT IN CULTIVATORS.

The Schedule referred to in these Letters Patent and making part of the same.

TO ALL WHOM IT MAY CONCERN:

Be it known that we, B. C. COCHRAN, T. W. COCHRAN, and JOSEPH M. COCHRAN, of Pana, in the county of Christian, and in the State of Illinois, have invented certain new and useful Improvements in Cultivators; and do hereby declare that the following is a full, clear, and exact description thereof, reference being had to the accompanying drawings, and to the letters of reference marked thereon, making a part of this specification.

In the annexed drawings, A represents the axle, having a suitable tongue, B, and wheels C C. D represents the metallic band resting upon the axle A, and extending about equidistant in front and rear of the said axle. This band forms the frame of the cultivator, and upon which is supported the seat, and to which the shovels are connected, being secured upon the axle near each wheel, but below the tongue on each side and passing over it, as shown. On each side of the tongue are the shovel-frames G G, which are connected to the band D by means of the swivels Y, so that they readily move laterally whenever so desired. These frames G G may be of one or two pieces of metal, spread apart at the rear and held so by the braces w w. It will be seen that one portion of each frame G is shorter than the other, and has each a shovel, i, connected at its lower extremity. E represents the seat for the driver, which is secured upon the rear portion of the frame D by means of suitable braces, and is provided with a metallic plate, a, upon each side. These plates a a are notched, x x x, to receive and catch the levers F F, to hold the plough or shovel-frames as required. The levers F F are made in an L-shape, being secured by means of their pivots, z z, at the bend to the rear part of the frame D, while the forward ends are connected to the metal loops b b, which are riveted to the shovel-frames G. By allowing the levers to catch in the lower notch x of the seat-plates a a, the shovels penetrate deeper in the earth than when the said levers are caught higher up in the seat, or the ploughs are entirely elevated above the earth, as may be desired. To each of the shovel-frame stays w w there is attached a vertical rod, H H', which two are connected together above the axle by the bar m, for shifting the ploughs from right to left. The rod H being longer than the rod H' extends up near the seat, so that the driver, by a lateral motion of this rod, shifts the two shovel-frames by a single operation. The shovels may be brought nearer together or separated farther by means of the stays w w, which can be extracted and placed in other openings made for the purpose in the shovel-frames.

Having thus fully described our invention, what we claim as new, and desire to secure by Letters Patent, is—

1. The metallic frame D, with seat E, plates a a, plough-frames G G, and ploughs i i, all constructed, arranged, and operating in the manner substantially as and for the purposes herein specified.
2. The shovel-frames G G, arranged with rods H H' and m, for shifting the loops b b and levers F F, for elevating the shovels, in the manner as set forth.

In testimony that we claim the foregoing, we have hereunto set our hands this 22d day of February, 1867.

B. C. COCHRAN,
T. W. COCHRAN,
JOSEPH M. COCHRAN.
